UNITED STATES PATENT OFFICE.

THOMAS CURLEY, OF WALTHAM, MASSACHUSETTS.

DESIGN FOR A PEDAL-HUB.

SPECIFICATION forming part of Design No. 27,463, dated August 3, 1897.

Application filed June 4, 1897. Serial No. 639,476. Term of patent 14 years.

To all whom it may concern:

Be it known that I, THOMAS CURLEY, of Waltham, in the county of Middlesex and State of Massachusetts, have invented and 5 produced a new and original Design for Pedal-Hubs, of which the following is a specification, reference being had to the accompanying drawings, forming part thereof.

Figure 1 represents a plan view of a pedal-10 hub illustrating my new design. Fig. 2 represents an end view of the same.

The leading features of my new design consist of the hub and the members extending laterally therefrom and having the reduced 15 portions adjacent to their ends.

In the drawings the central portion 5 is

circular in cross-section and joins the annular enlargements 6 6, from which the members 7 7 extend at right angles to the central portion. On these members are the spiral 20 threads 8 8, and the end portions of the members are abruptly reduced in diameter at their upper and lower surfaces, as at 9 9, beyond which are the enlargements 10 10.

What I claim is—

25 The design for a pedal-hub as herein shown and described.

THOMAS CURLEY.
